(57) **CLAIM**

The ornamental design for an area luminaire, as shown and described.

DESCRIPTION

FIG. 1 is a top, front perspective view of an embodiment of the design;

FIG. 2 is a bottom, front perspective view of FIG. 1;

FIG. 3 is a top, rear perspective view of FIG. 1;

FIG. 4 is a rear view of FIG. 1;

FIG. 5 is a front view of FIG. 1;

FIG. 6 is a top view of FIG. 1;

FIG. 7 is a bottom view of FIG. 1;

FIG. 8 is a right side view of FIG. 1;

FIG. 9 is a top, front perspective view of an embodiment of the design;

FIG. 10 is a bottom, front perspective view of FIG. 9;

FIG. 11 is a top, rear perspective view of FIG. 9;

FIG. 12 is a rear view of FIG. 9;

FIG. 13 is a front view of FIG. 9;

FIG. 14 is a top view of FIG. 9;

FIG. 15 is a bottom view of FIG. 9;

FIG. 16 is a right side view of FIG. 9;

FIG. 17 is a top, front perspective view of an embodiment of the design;

FIG. 18 is a bottom, front perspective view of FIG. 17;

FIG. 19 is a top, rear perspective view of FIG. 17;

FIG. 20 is a rear view of FIG. 17;

FIG. 21 is a front view of FIG. 17;

FIG. 22 is a top view of FIG. 17;

FIG. 23 is a bottom view of FIG. 17; and,

FIG. 24 is a right side view of FIG. 17.

The broken lines show portions of the area luminaire that form no part of the claimed design.
